UNITED STATES PATENT OFFICE

101,983

DESIGN FOR A GLASS PLATE OR SIMILAR ARTICLE

James E. Duncan, 3d, and Robert A. May, Washington, Pa., assignors to The Duncan & Miller Glass Company, Washington, Pa., a corporation of Pennsylvania

Application January 31, 1936, Serial No. 60,910

Term of patent 7 years

To all whom it may concern:

Be it known that we, James E. Duncan, 3rd, and Robert A. May, both citizens of the United States and residents of Washington, Pennsylvania, have invented a new, original, and ornamental Design for a Glass Plate or Similar Article, of which the following is a specification, reference being had to the accompanying drawing forming part thereof.

In the drawing, Figure 1 is a top plan view of a glass plate, and Figure 2 is a central ver-

tical cross-sectional view through the plate shown in Figure 1, the dominant feature of the design being the particular wavy effect produced in the glass as shown.

We claim:

The ornamental design for a glass plate or similar article substantially as shown and described.

JAMES E. DUNCAN, 3RD.
ROBERT A. MAY.
